UNITED STATES PATENT OFFICE

ROBERT W. MILLER, OF CORTLAND, NEW YORK, ASSIGNOR TO THE BREWER-TITCHENER CORPORATION, OF CORTLAND, NEW YORK, A CORPORATION OF NEW YORK

KNUCKLE JOINT MEANS

Application filed June 11, 1929. Serial No. 370,024.

This invention relates to the art of making all-metal knuckle joints and more particularly to smooth working linked stop-joints such as are adapted for use upon collapsible automobile tops of the closed body type or the like. As applied exteriorly to opposite sides of motor cars, my improved hinged prop or top brace each comprises a pair of highly finished links that may be pivotally interconnected through my stop joint means. The free ends of said adjoined links may be respectively attached to the rear side portions of the car body and to the corresponding hood portions; such brace links normally serve to rigidly support the hood in erected position but still allow of its being collapsed rearwardly upon breaking of the complementary stop joints.

The primary object of my improvements is to provide for a durable, rattle-proof and highly finished joint of the character indicated, that can readily and economically be fabricated on a productive scale, also one in which its trunnion ends are neatly and wholly concealed between suitable cover or trim plates without requiring the trunnion ends to extend therethrough or to be otherwise exposed to view. The present invention further aims to devise a relevant method for making and assembling my parts such that the complementary links together with all necessary joint members, may be individually nickel and chrome plated prior to the assembly thereof and obviate the need for grinding or refinishing the fulcrum pin ends after the joint is assembled.

To this end and the accomplishment of other new and useful results, said invention further consists in novel features of structure and mode of manipulation, all of which will hereinafter be more fully set forth.

Reference is had to the accompanying two sheets of drawings which are illustrative of a specific embodiment of my invention particularly as applied to automotive purposes, in which like characters of reference indicate like parts, and in which:

Fig. 1 is a fragmentary elevational side view of an automobile body showing the

rear top portion thereof equiped with my improved knuckle joint mechanism.

Fig. 2 represents an enlarged plan view of the joint assembly shown in Fig. 1, while Fig. 3 is a top view thereof.

Fig. 4 shows the hinge-like formation of an adjoined end portion of one of my link members.

Fig. 5 indicates a transverse view as taken along line 5—5 of Fig. 4, while Fig. 6 shows an end view as taken along line 6—6 of Fig. 4.

Fig. 7 is a transverse sectional view of one of my trim plates and Figs. 8 and 9 respectively represent a special style of bushing and tapered pin that are adapted to cooperate with said plates.

Figs. 10, 11 and 12 show successive stages in the assembly of my stop joint and the manner in which complementary trim plates are made to interlock about the assembled links to constitute a finished pivot joint.

Referring first to Fig. 1, this is intended to schematically indicate certain conventional motor car elements that may be indirectly associated with my device, such as a body 1, a rearwardly collapsible top portion 2 and a body side prop 3, and the like. A brace means of the kind in question, generally comprises two or more link members designated as 4 and 5, that are interconnected by a breakable knuckle joint of the stop type indicated in its entirety by 6. In Fig. 1 said brace means is for ornamental reasons given a double curved or S shaped form of which the outermost free ends may be equiped with eye-like bosses; one such end pivotally engages the body prop 3 while the other may be similarly attached to an upper side portion of the body top at 7. As will be understood, this particular style of stop linkage is intended to be broken when the top is collapsed rearwardly in the conventional fashion. Instead of the described single jointed link, a double jointed link may likewise be resorted to.

In Fig. 2, the full lined position represents the brace links placed in their normal or operative thrust relation while the dotted line position, indicates the joint as broken; said

joint is here shown as fashioned from substantially straight links but this is an immaterial detail since the present invention is more largely concerned with improving the pivotal joint therebetween. The adjoined end portion of each such link may be drop forged or otherwise formed up in the fashion detailed in Figs. 4 to 6 inclusive. Said links may be fabricated from solid oval bar stock preferably of steel, such as is cross-sectionally represented in Fig. 6. The knuckle joint or socket end portion of each link may first be upset into an enlargement adapted to form the substantially rectangular shank head 8 having its extremity simultaneously struck up by die means into the laterally offset disc-like pivot boss or hinge leaf 9.

It will be observed that the circular or disc-like outermost flat face 9A of said boss is preferably kept aligned with one of the head sides while the inner or rubbing boss face 9B is shown as medially depressed with respect to the head face width W. While striking up said boss 9, there may at the same time be indented, a relatively shallow cylindrical countersink 10 and also a centering pit 11. The latter serves for center purposes when drilling through the originally solid boss 9. The shank end may thereupon be turned over to spot the rubbing face 9B and said drilled boss hole may now be enlarged and reamed to form the tapered or cone-shaped socket 12 in the manner indicated by dotted outline in Fig. 5. For reason that will appear presently, the larger diameter of said cone is made to lie contiguous to the inner boss face 9B while the contracted neck thereof may be given a smaller bore size designated as "D".

Attention will now be directed to the trim plate 13 which may be turned up from suitable metal stock as a screw machine product. As cross-sectionally indicated in Fig. 7, said plate preferably comprises a button-like cover portion 13A of which one, namely the inner face is kept substantially flat to provide for a stop shoulder 13B from which there projects an expandable tubular rivet member 13C, as shown. It is pointed out that the domed exterior surface of said button 13A is preferably kept perfectly smooth and free from any aperture or other irregularities such as would be likely to mar the finished appearance thereof as applied to present purposes.

Fig. 8 shows an interlocking bushing 14 preferably made from soft brass or other relatively ductile metal, and this is given an internal diameter adapted to snugly receive said outwardly projecting plate rivet 13C. The outside tube diameter D is approximately kept to the contracted neck size D of the tapered socket 12 while the bush length L is preferably made slightly longer than the head face width W. The described joint ele-

ments may be expanded into place in a novel manner by the use of a doubly tapered wedge pin 15 such as is shown in Fig. 9, or by other suitable means.

The improved mode of assembling my knuckle joint is disclosed by Figs. 10 to 12 inclusive, which are taken transversely through complementary finished pivot bosses and their associated interlocking elements.

As a first step, two of said hinge-like bosses are assembled with their rubbing faces 9B placed in abutting relation. The corresponding larger diameter of their respective tapered sockets are thereby brought into registry to constitute an undercut cavity between the contracted ends thereof. The bushing 14 is next inserted therethrough and the overhanging ends crimped over into the respective head countersinks as shown in Fig. 10 where the bushing is made to serve as a tie piece for holding said bosses in alignment and against separation.

As a next step, the wedge pin 15 may be placed into the bush interior and the expandable plate rivet 13C initially assembled in the manner indicated by Fig. 11. If thereupon, pressure be applied to the oppositely disposed trim plates, this will forcibly spread out the respective rivets 13C and in turn radially expand the bushing 14 into the enlarged complementary sockets 13, thus pivotally interlocking the links 4 and 5 and serving to hold the complementary trim plates in place to constitute a unitary link structure. The described cavity disposed around said tube affords a clearance space into which the center region of the tube may be enlarged. The resulting interiorly undercut walls of the tube in turn provide for grip means adapted to interlockingly receive the expanded tubular plate rivets, thus constituting a simple and neatly finished means for holding the trim plate in place. In practice, the outermost diameter of the complementary trim plates is generally made sufficiently large to fully cover the interposed bosses 9.

It is further preferred to have the stop shoulders 13B come into abutment with the respective outermost boss faces 9A and to this end, the adjacent innermost ends of the expanded tubular plate rivets 13C may be kept slightly spaced. As will be understood, the interlocking hinge elements of my device are to be so proportioned and installed as to permit of a relatively free movement between the adjoined links 4 and 5; this is preferably attained by having the bush grip the tapered bore of one link boss while leaving the adjacent boss reasonably free to fulcrum therearound. As used for automobile tops, it is customary to provide for a stop toe or abutment face 8A disposed in an offset relation about the center of the pivot joint; it will be obvious however that the cited stop member is not an essential feature since the described

joint may readily be applied to jointed links that are not so provided. While it is preferred to simultaneously crimp the pintle 14 into its surrounding cavity by forcibly expanding the plate rivet 13C into place as described, the same result may also be attained by first interiorly crimping said chamber and thereupon expanding one or both trim plates therein by suitable means.

- 10 The following points emphasize the advantages that are inherent to my improved mode of fabricating such joints particularly as applied to automotive purposes, where the described type of hood brace is furnished and 15 sold as a highly finished product. In the conventional style of linked joints of this kind, the washer member corresponding to my trim plate 13 is ordinarily drilled through its center region and a rivet is inserted there- 20 in; the respective ends of said through rivet are thereupon upset to hold said washer plates in place. The usual procedure is to first separately grind, finish and copper plate each of the steel links and to similarly treat 25 the washer plates, whereupon these semi-finished parts are assembled and riveted together. As will be apparent, the upset rivet ends that project through the plated washer surface, must however still be independently 30 ground and polished to properly trim the joint; the exposed rivet ends together with the joint assembly as a whole are finally re-coppered and made ready for taking their finishing coating of nickel and chrome plate. 35 After extended use with the cited conventional washer plate, the riveted pin end tends to work loose and thus cause a ring-like defect that mars the highly finished outer plate surface.
- 40 On the other hand, this need for supplemental plating is entirely eliminated by the use of my devices, since no portion of the rivet pin is allowed to project through the trim plate to disfigure the exterior surface 45 thereof. In addition, the adjoined links 4 and 5 and likewise my trim plate may be completely plated in one and the same operation, and the individual parts made ready for final assembly in the manner described 50 in connection with Figs. 10 to 12. The nickel and chrome plating is thereby uniformly distributed throughout, including all crevices between the joint rubbing surface and there is far less likelihood of the finished cover 55 plate faces becoming rusted in spots owing to imperfect continuity on part of the plating coat.

It is understood that the described joint devices also find application to purposes other than automotive brace links of the hinged type, it being emphasized that my described trim plate devices may in similar manner be applied to so-called dummy joints which do not actually provide for a pintle knuckle joint 60 but merely simulate such, and that various

changes in the details and mode of manipulation thereof may be resorted to in likewise carrying out my illustrative structural embodiment, all without departing from the spirit and scope of my invention, heretofore described and more particularly pointed out in the appended claims.

Claims:

1. Jointed brace means comprising a pair of relatively movable shank-like members 75 respectively equiped with apertured bosses, internally chambered pintle means serving to pivotally interconnect said bosses, and a trim-plate telescopically associated with one end region of said pintle and which associated parts are interlockingly expanded into each other without unduly restraining the relatively movable members.

2. In a knuckle joint means adapted to pivotally connect two members comprising in 25 combination, a relatively flat pivot boss for each such member, each such boss having an axially contracted hole therethrough and which complementary bosses are adapted to lie face to face with the respective enlarged 30 hole portions placed in abutting registry to constitute a radially undercut cavity between the respective contracted hole ends, tie means of the expansible tubular type extending through and pivotally cooperating 35 with the respective contracted hole ends, and wedge means including a tapered pin entered within and serving to forcibly expand a medial region of said tie means into said 40 cavity.

3. In a knuckle joint means adapted to pivotally connect two members comprising in 45 combination, a relatively flat pivot boss for each such member, each such boss having a contracted hole therethrough and which complementary bosses are adapted to lie 50 face to face with the respective enlarged hole portions placed in abutting registry, tie means of the hollowed pintle type mounted through said holes, wedge means 55 disposed interiorly of said tie means, and a trim plate provided with an expansible means adapted to be interposed between said 60 wedge and the interior of the aforesaid tie means, said wedge means serving to forcibly open 65 said expansible means into interlocked relation with the tie means.

4. In a knuckle means of the stop joint type adapted to pivotally connect complementary brace links of which each such link 120 comprises a head portion terminating in a transversely disposed abutment, the combination of a disc-like pivot boss associated with each such head in a laterally offset relation to a marginal portion of its abutment, 125 said disc-like bosses each being provided with an axially contracted hole and which complementary bosses are adapted to lie face to face with the respective enlarged hole ends placed in abutting registry, tubular means extend- 130

ing through said holes with the respective ends thereof crimped over the opposite free ends of said holes, and plate means provided with an expansible means adapted to enter said tubular means and interlock therewith.

5. Jointed brace means comprising a pair of relatively movable shanks respectively equipit with apertured bosses, tubular pintle means interconnecting said bosses, said pintle 10 having an interior cavity that is radially undercut with respect to the end openings thereof, a separate trim-plate for each pintle end, each such plate being provided with expansible plug means adapted to enter the respective 15 end openings, and a common wedge means interposed between and serving to expand both of said plugs into the pintle cavity.

In testimony whereof, I have herewith set my hand this 10th day of June, 1929.
